PLATFORM SHOE

Ernest Ferriero, Brooklyn, N. Y.

Application July 26, 1944, Serial No. 546,667

10 Claims. (CL 36—17)

This invention relates to new and useful improvements in shoes, and platforms thereof.

The invention is particularly intended for play shoes. It is characterized by certain constructions of each shoe. It is proposed that each shoe include an inner sole and a casing for covering the top and sides of said inner sole and including a top casing section engaging over the top of the inner sole and an edge strip casing section secured to the edges of said top section and engaging beneath the edge portions of said inner sole, a shoe upper is attached to said casing.

A new and novel welting is attached to the said edge strip section and is cemented to the inner sole. A wedge heel with a casing is mounted beneath the shank and heel of the inner sole.

It is also proposed to provide another welting attached to the bottom edges of the casing of the wedge heel. An outer sole is secured to said weltings.

The shoe may also be provided with a shank stiffener.

The constructions of the weltings may be modified.

Another object of the invention is the construction of an article as mentioned which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevational view of a shoe constructed in accordance with this invention.

Fig. 2 is a plan view of Fig. 1.

Fig. 3 is a bottom view of the shoe shown in Figs. 1 and 2 but drawn on a reduced scale.

Fig. 4 is a fragmentary enlarged vertical sectional view taken on the line 4—4 of Fig. 1.

Fig. 5 is a fragmentary enlarged vertical sectional view taken on the line 5—5 of Fig. 1.

Fig. 6 is a perspective view of a piece of the welting used.

Fig. 7 is a fragmentary enlarged vertical sectional view taken on the line 7—7 of Fig. 2.

Fig. 8 is a fragmentary perspective view of a piece of welting constructed in accordance with another form of this invention.

Fig. 9 is a fragmentary enlarged vertical sectional view similar to Fig. 4 but illustrating a modified form of the invention.

The shoe and the method for attaching the wedge heel in position, is characterized by providing the shoe with an inner sole 10. This inner sole may be a piece of fibrous material. A casing 11 for covering the top and sides of the inner sole 10 is formed from a top casing section 12 stitched to an edge strip casing section 13. The top section 12 extends across the top of the inner sole 10 and is permanently secured 10 in position by adhesive material 14. The shoe is provided with an upper 15 which is secured to the casing 11. More particularly, the bottom edge or edges of the upper 15 engage in between the casing section 12 and 13, forming the casing 11. These parts are secured together by stitches 16.

A welting 17 is attached to the edge strip portion 13 by several lines of stitches 18. This welting 17 is formed with a lining layer 19 and an 20 outer layer 20 bent around the outer edge of the lining layer 19. Cement 21 is used between the 25 welting 17 and the adjacent portions of the edge strip section 13 and the bottom face of the inner sole 10.

The shoe is also provided with a wedge heel 22 of wood or other hard material. This wedge heel is covered by a cloth casing 23 which is disposed around the side and partially across the top and bottom faces by adhesive material 24.

The welting 17 is secured to the wedge heel 22 by adhesive material 25. Another welting 17' is attached to the bottom edge of said casing 23. This welting 17' includes a lining 19' and a covering sheet 20' secured together by adhesive material 21'. The welting 17' is also secured to the bottom edge of the casing 23 by stitches 28.

An outer sole 29 is secured to the welting 17 and 17' by a line of stitches 30 engaged between the outer edge portions of these parts.

The wedge heel 22 and the shank portion of the shoe are provided with a shank stiffener 31. This shank stiffener 31 consists of a fiber material portion 32 and a strip of steel 33, secured together by rivets 34. The inner sole 10 is hollowed out for receiving the shank stiffener 31.

In Fig. 8 a piece of welting is shown constructed in accordance with a modified form. This welting has a lining 35 which has an outer edge portion 36 bent down and secured in position 50 by adhesive 37. An outer cover sheet 38 is engaged over the lining 35 and is secured in position by adhesive 39. This welting may be used in place of the welting previously described.

The dominating feature of the invention resides 55 in the construction of the casing 11 and the way

in which the casing is connected with the welt 17. Another feature resides in the construction of the wedge heel 22 with its covering casing 23 and the way in which this covering casing is attached to the welt 17. With the construction defined it is a simple matter to secure the outer sole 29 in position merely by using the stitches 30.

In the modified form of the invention disclosed in Fig. 9, the welt construction of the shoe has been modified. This welt has a top portion 40 which is a bottom continuation from the edge strip casing section 13. This top portion 40 is held in an outwardly extended position by a line of stitches 41. The welt also has a welt bottom portion 42 which is located beneath the welt top portion 40 and which extends inwards beneath the inner sole 10. The welt bottom portion 42 is secured to the bottom face and the inner sole 10 by adhesive material 43. A line of stitches 44 secures the welt top portion 40 together with the welt bottom portion 42. The outer sole 29' is illustrated as formed from several layers cemented together.

In other respects this form of the invention is similar to the first disclosed form, and identical parts may be recognized by the same numerals.

While I have illustrated and described the preferred embodiments of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A shoe, comprising an inner sole, a casing for covering the top and sides of said inner sole and including a top section engaging over the top of the inner sole and an edge strip section secured to the edges of said top section and engaging beneath the edge portions of said inner sole, a shoe upper attached on said casing, a welt attached to said edge strip section and cemented to said inner sole, a wedge heel with a casing mounted beneath the shank and heel of said inner sole, a welt attached to the bottom edges of said casing of said wedge heel, and an outer sole secured to said weltings.

2. A shoe, comprising an inner sole, a casing for covering the top and sides of said inner sole and including a top section engaging over the top of the inner sole and an edge strip section secured to the edges of said top section and engaging beneath the edge portions of said inner sole, a shoe upper attached on said casing, a welt attached to said edge strip section and cemented to said inner sole, a wedge heel with a casing mounted beneath the shank and heel of said inner sole, a welt attached to the bottom edges of said casing of said wedge heel, and an outer sole secured to said weltings, said weltings comprising lining layers and covering layers cemented together.

3. A shoe, comprising an inner sole, a casing for covering the top and sides of said inner sole and including a top section engaging over the top of the inner sole and an edge strip section secured to the edges of said top section and engaging beneath the edge portions of said inner sole, a shoe upper attached on said casing, a welt attached to said edge strip section and cemented to said inner sole, a wedge heel with a casing mounted beneath the shank and heel of said inner sole, a welt attached to the bottom edges of

said casing of said wedge heel, and an outer sole secured to said weltings, the bottom edge of said shoe upper being engaged between said top section and strip section, and stitches holding these parts together.

4. A shoe, comprising an inner sole, a casing for covering the top and sides of said inner sole and including a top section engaging over the top of the inner sole and an edge strip section secured to the edges of said top section and engaging beneath the edge portions of said inner sole, a shoe upper attached on said casing, a welt attached to said edge strip section and cemented to said inner sole, a wedge heel with a casing mounted beneath the shank and heel of said inner sole, a welt attached to the bottom edges of said casing of said wedge heel, and an outer sole secured to said weltings, said casing having its edges bent over the top and bottom edge portions of said wedge heel.

5. A shoe, comprising an inner sole, a casing for covering the top and sides of said inner sole and including a top section engaging over the top of the inner sole and an edge strip section secured to the edges of said top section and engaging beneath the edge portions of said inner sole, a shoe upper attached on said casing, a welt attached to said edge strip section and cemented to said inner sole, a wedge heel with a casing mounted beneath the shank and heel of said inner sole, a welt attached to the bottom edges of said casing of said wedge heel, and an outer sole secured to said weltings, said casing having its edges bent over the top and bottom edge portions of said wedge heel, said last-named welt being stitched to the bottom of said casing.

6. A shoe, comprising an inner sole, a casing for covering the top and sides of said inner sole and including a top section engaging over the top of the inner sole and an edge strip section secured to the edges of said top section and engaging beneath the edge portions of said inner sole, a shoe upper attached on said casing, a welt attached to said edge strip section and cemented to said inner sole, a wedge heel with a casing mounted beneath the shank and heel of said inner sole, a welt attached to the bottom edges of said casing of said wedge heel, and an outer sole secured to said weltings, and a shank stiffener for said shoe.

7. A shoe, comprising an inner sole, a casing for covering the top and sides of said inner sole and including a top section engaging over the top of the inner sole and an edge strip section secured to the edges of said top section and engaging beneath the edge portions of said inner sole, a shoe upper attached on said casing, a welt attached to said edge strip section and cemented to said inner sole, a wedge heel with a casing mounted beneath the shank and heel of said inner sole, a welt attached to the bottom edges of said casing of said wedge heel, an outer sole secured to said weltings, and a shank stiffener for said shoe, mounted between said wedge heel and said inner sole.

8. A shoe, comprising an inner sole, a casing for covering the top and sides of said inner sole and including a top section engaging over the top of the inner sole and an edge strip section secured to the edges of said top section and engaging beneath the edge portions of said inner sole, a shoe upper attached on said casing, a welt attached to said edge strip section and cemented to said inner sole, a wedge heel with a casing mounted beneath the shank and heel

of said inner sole, a welting attached to the bottom edge of said casing of said wedge heel, and an outer sole secured to said weltings, said welting comprising an inner layer having an edge bent upon itself and cemented in position, and a covering sheet cemented upon said inner layer.

9. A shoe, comprising an inner sole, a casing for covering the top and sides of said inner sole and including a top section engaging over the top of the inner sole and an edge strip section secured to the edges of said top section and having a bottom outwardly extending portion forming a welt top portion, a welt bottom portion attached to said welt top portion and extending inwards and attached to the bottom face of said inner sole, a shoe upper attached on said casing, and an outer sole attached to said welt and to the bottom of the inner sole.

10

15

10. A shoe, comprising an inner sole, a casing for covering the top and sides of said inner sole and including a top section engaging over the top of the inner sole and an edge strip section secured to the edges of said top section and having a bottom outwardly extending portion forming a welt top portion, a welt bottom portion attached to said welt top portion and extending inwards and attached to the bottom face of said inner sole, a shoe upper attached on said casing, and an outer sole attached to said welt and to the bottom of the inner sole, said welt top portion and said welt bottom portion being sewed together.

ERNEST FERRIERO.
